Atty.

UNITED STATES PATENT OFFICE

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

SOLDERING IRON.

Application filed May 5, 1924. Serial No. 710,990.

To all whom it may concern:

Be it known that I, WILLIAM J. FRISBIE, a citizen of the United States, and a resident of Chicago, in the county of Cook and State 5 of Illinois, have invented certain new and useful Improvements in Soldering Irons, of which the following is a specification.

My invention relates to soldering irons of the type in which the combustion fuel is 10 alcohol, or some hydrocarbon oil such as gasoline. The invention concerns particularly such structures in which a combustion section in the form of a Bunsen burner extends coaxially with reference to a handle 15 section which is provided with a fuel reservoir, with a gas generating structure and a priming cup interposed between the burner and handle part, the structure being adapted to be set up on end during the priming operation or when not in use. A soldering iron 20 of this type is disclosed in my application, Serial No. 693,028, filed February 15, 1924. As the metallic handle part forming the reservoir becomes hot through conduction 25 of heat, the constructions heretofore patented provided a wooden grip or sleeve fitting over the handle part and provided with a wooden removable cap which forms also a supporting base for the iron, the cap being 30 removable in order that the filling plug at the lower end of the reservoir might be accessible. This grip construction has many disadvantages. In the first place, the grip which intimately surrounds the reservoir 35 section soon becomes uncomfortably hot. In the second place, when the iron is inverted and the reservoir filled there is usually an overflow of combustion fluid which will flow 40 down along the outside of the grip or work its way in between the grip and the reservoir wall. In the third place when the iron is set up on end after filling and the priming cup is filled for starting purposes some of the oil usually escapes from the cup 45 and flows down along the outside of the grip or finds its way in between the upper end of the grip and the reservoir walls. The result is that when the priming fluid is ignited the flame immediately jumps down to the overflow oil on the outside of the grip and between the grip and reservoir and the user becomes frightened and the grip becomes hot. The object of my invention is therefore to provide such construction and arrangement as will avoid the above disadvantages.

I provide a grip in the form of a cylindrical shell of fibre or other suitable material of greater diameter than the metallic reservoir section, and for this shell I provide a metallic base by means of which the shell may be supported from the end of the reservoir section to be concentric with the reservoir but spaced away therefrom by an insulating air space, the conical priming cup serving to guide and to hold the upper end 60 of the shell in proper spaced relationship. In the base I provide holes for the escape of any accumulated liquid and in the sides of the shell I provide air circulating holes so that heat conducted through the reservoir 65 walls may be rapidly carried away and the grip kept cool. With this arrangement the entire grip can be removed while the iron is being filled and then the reservoir section 70 can be wiped dry of any surplus or spilled oil before the grip is again applied. I also provide arrangement for preventing overflow oil from flowing from the priming cup into the inside of the grip, and any oil which may flow from the priming cup to the outside of the grip will be rapidly evaporated 75 or burned away before the grip can be heated to any extent.

On the accompanying drawing I show an iron of my improved construction. 85

On the drawing,

Fig. 1 is a side elevational view partly in vertical diametral section,

Fig. 2 is a bottom view of the grip shell base, and 90

Fig. 3 is a sectional view on plane 3—3, Fig. 1.

The tubular body part 10 provides the reservoir 11 for the combustion fuel. In the lower end of the tubular body is the bushing 12 for receiving the filler plug 13 which threads therein. Secured in the upper end of the tubular body is the bushing 14 which supports the generator and valve fitting 15, the frusto-conical priming cup 16 being 95 clamped between the bushing and the fitting to surround the gas generating space 17 within the fitting. At its upper end the fitting seats the gas outlet 18 and supported on the fitting concentric with the tip is the burner tube 19 which at its upper end supports a soldering tip 20, the burner tube having the air inlets 21 suitably spaced. Just above the priming cup the fitting has the lateral extension 22 through which 100 105 110

passes the valve stem 23 with the handle 24 at its outer end. The inner end of the stem forms the conical valve 25 which cooperates with the seat 26 to control the flow 5 of gas from the generating chamber through the passageways 27 and 28.

The grip for the iron comprises the cylindrical shell 29 of fibre or other suitable material which shell is of a diameter greater 10 than that of the tubular body 11. The shell has the sheet metal base or cup 30 secured thereto in any suitable manner as by means of indentations 31 which project from the base into the shell. The bottom 15 of the base is flared as indicated at 32 to provide ample seating surface for holding the iron in upright position. The bottom of the shell base has its middle section 33 deflected inwardly to form the space 34 for 20 accommodating the head 35 of a screw 36 which extends axially from the base bottom to engage in the threaded passageway 37 provided in the plug 13 for the fuel reservoir. When the grip structure is applied 25 and secured by means of the screw the shell will be concentric with the reservoir body 11 but spaced away therefrom by considerable air space, the only contact between the grip structures and the reservoir body being 30 along the small area where the grip base engages against the filler plug. The grip is thus amply protected from the heat conducted along the metal reservoir body, and in order to readily dissipate any heat, I 35 provide a zone of air holes 38 in the shell near the lower end thereof, and a zone of air openings 39 near the upper end of the shell, these lower and upper openings permitting the circulation of air through the 40 space between the shell and the reservoir body so that there can be no accumulation of heat.

The conical priming cup will serve to 45 guide the grip shell into place when it is applied to the iron and to then hold it properly spaced with reference to the reservoir body. The upper edge 40 of the priming cup is curled outwardly and downwardly to receive the upper end of the shell but 50 to keep its edge a sufficient distance away from the shell so that overflow fluid will be prevented from finding its way in between the shell and the cup. Any overflow or surplus fuel will then merely drop down 55 or run along the outside of the shell where it will be in greater part evaporated or quickly burned away when the priming cup is ignited. When the iron is to be filled the grip structure is removed and the filler plug 13 is withdrawn. Frequently there will be 60 an overflow of fuel but in this case the user can wipe off the outside of the reservoir before applying the grip structure. However, should any oil be left or should any 65 leak out of the reservoir when the iron is

in upright position, such oil can flow out through the holes 41 provided in the bottom wall of the shell base.

I have shown the wick 42 in the fuel reservoir which extends upwardly through 70 packing 43 into the chamber 17 where the fuel is converted into gas by the heat of the burning fuel in the priming cup, the generated gas going up through the passageways 27 and 28 to the burner tip 18 under 75 control of the valve structure.

I thus provide a strong, simple and rigid grip structure for the iron which will always be sufficiently cool to permit comfortable operation of the iron. Any overflow 80 when the priming cup is filled can reach only the outside of the grip shell where it will quickly evaporate or burn away without unduly heating the shell while the iron is being primed.

I do not desire to be limited to the exact construction and arrangement shown and described as modifications may be made which will still come within the scope of the invention.

I claim as follows:

1. In a soldering iron of the class described, the combination of a tubular body part forming a reservoir for liquid fuel, a gas generator fitting mounted on the upper end of said body part, a burner extending from said fitting, a grip in the form of a tubular shell surrounding said body part but spaced therefrom to leave a heat insulating air space, a filler plug for the lower end of said body part reservoir, and means for detachably securing said grip to said plug.

2. In a soldering iron of the class described, the combination of a hollow body 105 part forming a reservoir for liquid fuel, a generator fitting mounted on the upper end of said body part, a burner mounted on said fitting, a plug for closing the lower end of said body part reservoir, and a grip in the 110 form of a tubular shell secured to said plug to surround said body part and to be spaced therefrom by an insulating air passageway.

3. In a soldering iron of the class described, the combination of a hollow body 115 part forming a reservoir for liquid fuel, a gas generator fitting mounted on the upper end of said body part, a burner mounted on said fitting to receive the generated gas, a plug threading into the lower end of said body part to close the reservoir, a supporting base for the iron secured to said plug, and a tubular grip extending from said base to surround said body part and to be spaced therefrom by a heat insulating air space.

4. In a soldering iron of the class described, the combination of a tubular body part forming a reservoir for liquid fuel, a generator fitting on the upper end of said body part, a burner mounted on said fitting 130

- to receive the generated gas, a grip structure comprising a base and a tubular shell extending therefrom, and means for detachably securing said base to the lower end of said body part whereby said grip structure may be removed when said reservoir is filled, said grip structure when in place being separated from said body part by a heat insulating air space.
- 10 5. In a soldering iron of the class described, the combination of a tubular body part providing a reservoir for liquid fuel, a generator fitting on said body part co-axial therewith, a burner mounted on said fitting 60
- 15 to receive the generated gas, a priming cup concentric with said body part and surrounding said generator fitting, a tubular grip surrounding said body part and separated therefrom by a heat insulating air 65
- 20 space, and means detachably securing said grip to the lower end of said body part, said priming cup receiving the upper end of said grip to assist in holding it in spaced 70
- 25 position relative to said body part.
- 25 6. In a soldering iron of the class described, the combination of a tubular body part providing a reservoir for liquid fuel, a generator fitting mounted on the upper end of said body part co-axial therewith, a 75
- 30 burner mounted on said generator fitting to receive the generated gas, a priming cup surrounding said fitting concentric with said body part, a closure plug for said reservoir at the lower end of said body part, a detachable 80
- 35 tubular grip secured at its lower end to said plug and spaced throughout its length from said body part for the circulation of air, said priming cup receiving the upper end of said grip to assist in holding 85
- 40 it in spaced relationship with said body part.
7. In a soldering iron of the class described, the combination of a tubular body part providing a fuel reservoir, a generator fitting mounted on top of said body part co-axial therewith, a burner structure mounted on said fitting to receive the generated gas, a priming cup surrounding said fitting concentric with said body part, a grip 90
- 45 structure comprising a base and a tubular grip section concentric with but separated from said body part by a heat insulating air space, means for detachably securing said base to said plug, said priming cup being of a diameter to receive the upper end of said grip section, said base serving to support 95
- 50 said iron in vertical position.
8. In a soldering iron of the class described, the combination of a tubular body 100
- 55 part forming a reservoir for liquid fuel, a generator fitting mounted on the upper end of said body part, a burner mounted on said fitting, a priming cup surrounding said fitting concentric with said body part, a grip in the form of a cylindrical shell surrounding said body part but separated therefrom by a heat insulating air space, means detachably securing said grip at its lower end to said body part, said priming cup being of a diameter to receive and support said grip at its upper end, the upper edge of said cup being deflected to overhang the upper end of said grip whereby to prevent the flow of priming fluid between the cup and grip.
9. In a soldering iron of the class described, the combination of a tubular body part forming a reservoir for liquid fuel, a generator fitting mounted on the upper end of said body part concentric therewith, a burner mounted on said fitting, a priming cup surrounding said generator fitting concentric with said body part, a grip in the form of a cylindrical shell surrounding said body part but separated therefrom by a heat insulating air space, means detachably securing said grip at its lower end to the body part, the upper edge of said cup being deflected laterally and downwardly to form an annular space for receiving the upper end of said grip whereby to support said grip relative to said body part and to prevent overflow priming oil from entering between the cup and the grip.
10. In a soldering iron of the class described, the combination of a tubular body part forming a reservoir for liquid fuel, a closure plug for said reservoir engaging in the lower end of said body part, a gas generating fitting mounted on the upper end of said body part, a burner mounted on said fitting to receive the generated gas, a priming cup surrounding said fitting concentric with said body part, a grip structure comprising a base and a tubular grip section surrounding said body part but separated therefrom by a heat insulating air space, means for detachably securing said base to said plug, the upper edges of said cup being deflected laterally and downwardly to form an annular space for receiving the upper end of said grip section whereby to assist in supporting the grip structure and to prevent entrance of overflow priming fluid between said cup and grip section.
- In witness whereof, I hereunto subscribe my name this 29th day of April, A. D., 1924

WILLIAM J. FRISBIE.
